DESIGN FOR A HOT WATER HEATER

Edward H. Stempel, Albert Lea, Minn., assignor to
American Gas Machine Company, Albert Lea,
Minn., a corporation of Minnesota

Application May 26, 1944, Serial No. 113,763

Term of patent 14 years

(Cl. D81—2)

To all whom it may concern:

Be it known that I, Edward H. Stempel, a citizen of the United States and residing in the city of Albert Lea, Freeborn County, State of Minnesota, have invented a new, original, and ornamental Design for Hot Water Heaters, of which the following is a specification, reference being had to the accompanying drawing, forming a part thereof.

Figure 1 is a front elevation of a hot water heater showing my new design; and

Figure 2 is a side elevation of the same.

I claim:

The ornamental design for a hot water heater, as shown.

EDWARD H. STEMPEL.
